UNITED STATES PATENT OFFICE.

GEORGES ROESCH, OF LONDON, ENGLAND, ASSIGNOR OF ONE-HALF TO CLEMENT TALBOT LIMITED, OF LONDON, ENGLAND.

DESIGN FOR A BODY OF AN AUTOMOBILE.

52,673.

Specification for Design.

Patented Nov. 12, 1918.

Application filed November 23, 1917. Serial No. 203,633. Term of patent 14 years.

To all whom it may concern:

Be it known that I, GEORGES ROESCH, a citizen of the Swiss Confederation, residing at Barlby Road, Ladbroke Grove, London, England, have invented a new, original, and ornamental Design for a Body of an Automobile, of which the following is a specification, reference being had to the accompanying drawing, forming part thereof.

The figure is a side perspective view of

the body of an automobile illustrating my new design.

I claim:

The ornamental design for a body of an automobile, as shown.

GEORGES ROESCH.
